FLUSH TANK VALVE

Yervant H. Kurkjian, Hawthorne, N. J.

Application April 30, 1940, Serial No. 332,603

4 Claims. (Cl. 4—56)

This invention relates to flush tank valves, and has for one of its objects the production of a simple and efficient valve which is so constructed as to tightly seat upon the valve seat, through the medium of the weight of the water within the tank acting upon the valve.

A further object of this invention is the production of an efficient flush tank valve which may be economically constructed and assembled and which will provide an efficient closure for the valve seat.

Other objects and advantages of the present invention will appear throughout the following specification and claims.

In the drawing:

Figure 1 is a vertical sectional view of the valve in a closed or seated position and illustrating one form of my invention, a certain portion of the valve being shown in elevation;

Figure 2 is a bottom plan view of the valve shown in Figure 1;

Figure 3 is a side elevational view of the valve in a partly open position, a portion of the valve being shown in section;

Figure 4 is a vertical sectional view of a modified form of the invention;

Figure 5 is a side elevational view of the upper section of the type of valve illustrated in Figure 4, a certain portion being shown in section;

Figure 6 is a side elevational view of the lower section of the type of valve shown in Figure 4, a certain portion being shown in section;

Figure 7 is a vertical sectional view of a further modified form of valve;

Figure 8 is a top plan view of the valve disc shown in Figure 7, the stem being shown in transverse section.

By referring to the drawing, it will be seen that A designates the conventional valve seat used in conjunction with toilet valves, and the like. A hollow flush valve 10 is adapted to fit snugly upon the valve seat A, and this hollow flush valve 10 is preferably formed of rubber or other resilient material and comprises an inverted conical portion 11, the lower edge of which is provided with a reinforcing upturned bead or flange portion 12 which is spaced away from the side walls of the conical portion 11, to provide a water-receiving channel, as shown. The hollow flush valve 10 is provided with an upstanding annular flange 13 along its upper edge and a partition 14 is formed within the hollow flush valve 10, as shown in Figure 1, preferably formed integral with the valve 10. The partition 14 is inset with respect to the outer edge 15 of the valve 10 to provide

a water-containing compartment 16. A stem 17 of the conventional type is threaded into engagement with a cap 18 fitted within the depending nipple 19.

The operation of the device is as follows:

The valve 10 will operate in the usual manner to rise vertically with respect to the seat A, and uncover the valve seat. The buoyancy of the valve 10 will permit the valve 10 to rise when the valve 10 is moved from the valve seat A for the purpose of moving the valve to an open position. As the tank, of which the valve seat A forms a part, empties, the water will rush through the valve seat A and contact the flange or upturned bead 12 tending to pull the inverted conical portion 11 of the valve 10 to a firm seating position upon the valve seat. The water which will naturally fill the compartment 16 will add additional weight to the valve also tending to force the valve down tightly upon the valve seat A. However, while the valve 10 is in a raised position from its seat and is immersed within the water contained in the tank, the buoyancy of the valve will tend to counteract the weight of the water within the compartment 16. As soon as the water falls below the level of the edge 15, however, the water within the compartment 16 will tend to add additional weight to the valve and cause the valve 10 to become more firmly seated upon the valve seat A as soon as the water within the tank is drained off through the opening provided by the valve seat A.

It should be understood that I have provided two distinct features which will tend to force the valve 10 upon its seat, one being the upturned bead or flange 12 against which the downwardly rushing water through the valve seat A will contact tending to pull the valve 10 to a seating position, and the other feature being the weight of the water within the compartment 16 which will tend to firmly force the valve 10 to a seating position upon the valve seat A.

In Figure 4, I have shown a modified form of the invention wherein the valve 10a is formed of flexible material, such as rubber and the like, and comprises an upper section 20 and a lower section 21. The lower section 21 comprises an inverted cone-like structure having an open lower end 22 similar to that shown in Figure 1, and the lower edge of the lower section 21 is provided with an upturned bead or flange 23 similar to the flange or bead 12. The lower section 21 is provided along its upper edge with an inwardly extending annular bead 24 which snugly rests within an annular channel 25 formed in the lower edge of the upper section 20 to pro-

vide an interlocking fit between the upper and lower sections 20 and 21. A stem 26 is secured to a cap 27 carried by a nipple 28 supported by the bottom wall 29 of the upper section 20. The upper section 20 is also provided with an upstanding annular flange 30 to provide a water-receiving compartment 31 similar to the compartment 16. By means of the structure just described it will be seen that the upper and lower sections 20 and 21 are separable.

In Figure 7, I have shown a further modified type of my invention, wherein a flexible valve 32 is illustrated, preferably formed of rubber or other resilient material, and having an inverted cone-like lower portion 32. The lower portion 32 is provided with an open lower end 33 which lower end terminates in an upturned bead or flange 34. The valve 32 is provided with an upstanding annular flange 35 and at the point of junction between the flange 35 and the inverted conical portion 32 is provided an annular channel 36, in which channel 36 is fitted the edge of a stem engaging disc 37, to which disc 37 is secured the stem 38. The disc 37 may be formed of rubber or any other suitable material, and is preferably provided upon its upper and lower faces with channels 39 and 40. The disc 37 provides a partition between the lower and upper ends of the valve 32 and constitutes a floor for the water-containing compartment 41, similar to the compartment 16.

It should be understood that certain detail changes in the mechanical construction may be employed without departing from the spirit of the invention so long as such changes fall within the scope of the appended claims.

Having described the invention, what I claim as new is:

1. A tank valve of the class described comprising a flexible hollow body, said body having a substantially inverted cone-shaped lower portion,

the lower portion having an open lower end and an upturned reinforcing flange formed around the open lower end and spaced from the sides of the body to provide a water-receiving channel into which water flowing by the valve will impinge to pull the inverted cone-like portion tightly upon a valve seat.

2. A flush tank valve comprising a flexible body formed of a pair of separable sections, one section having an inwardly extending annular bead around one end thereof, and the other section having an annular channel adapted to receive the bead in interlocking engagement for firmly holding the sections together, one of the sections being formed of resilient material for facilitating the assembly of the sections and the separation of the sections.

3. A flush tank valve of the class described comprising a hollow body, the lower end of which comprises a substantially inverted cone, the body having an annular channel formed intermediate the ends thereof and upon the inner face of the body, and a stem-supporting disc fitted within the body and inset with respect to the outer edge of the body and having its periphery fitting within the channel, the body being flexible and resilient to facilitate the placing the periphery of the disc in the channel and removal therefrom to permit replacement of the body independently of the disc, said disc constituting a floor for a compartment formed at one end of the body.

4. A flush tank valve of the class described comprising a pair of sections, one section having an annular channel, and the other section having a portion for fitting into said channel for detachably connecting the sections together, and one of the sections being flexible for facilitating the removal and replacement of one section independently of the other section.

YERVANT H. KURKJIAN.
